[57] **CLAIM**

The ornamental design for a front bezel mounting to a computer enclosure, as shown and described.

DESCRIPTION

FIG. 1 is a perspective view of a front bezel mounting to a computer enclosure showing our new design; FIG. 2 is a front elevational view thereof; FIG. 3 is a rear elevational view thereof; FIG. 4 is a left side elevational view thereof; FIG. 5 is a right side elevational view thereof; FIG. 6 is a top plan view thereof; FIG. 7 is a bottom plan view thereof; and, FIG. 8 is a perspective view of the front bezel mounting to a computer enclosure of FIG. 1 wherein the computer enclosure is shown in broken lines.

The broken lines shown in FIG. 8 are for illustrative purposes only and form no part of the claimed design.
